(57) **CLAIM**

The ornamental design for cannulated pedicle screw torque driver, as shown and described.

DESCRIPTION

FIG. 1 is a front view of an exemplary cannulated pedicle screw torque driver;

FIG. 2 is a top view of the cannulated pedicle screw torque driver of FIG. 1;

FIG. 3 is a bottom view of the cannulated pedicle screw torque driver of FIG. 1;

FIG. 4 is a rear view of the cannulated pedicle screw torque driver of FIG. 1;

FIG. 5 is a left view of the cannulated pedicle screw torque driver of FIG. 1; and,

FIG. 6 is a right view of the cannulated pedicle screw torque driver of FIG. 1.

Broken lines, if any included, in the drawings are for illustrative purposes only and do not form part of the claimed design.

1 Claim, 6 Drawing Sheets
